UNITED STATES PATENT OFFICE.

CLYDE S. OSBORN, OF BESSVILLE, MISSOURI.

SECTIONAL WASHER.

1,288,973.

Specification of Letters Patent. Patented Dec. 24, 1918.

Application filed April 5, 1918. Serial No. 226,896.

To all whom it may concern:

Be it known that I, CLYDE S. OSBORN, a citizen of the United States, residing at Bessville, in the county of Bollinger, State 5 of Missouri, have invented a new and useful Sectional Washer; and I do hereby declare the following to be a full, clear, and exact description of the invention, such as will enable others skilled in the art to which it 10 appertains to make and use the same.

The present invention relates to a sectional collar or washer, and has for its object to provide a device of this character which embodies novel features of construction where- 15 by it can be applied to a shaft at an intermediate point in the length thereof without the necessity of first removing any pulleys or wheels which may be fixed upon the shaft in order to slip the washer over the end of 20 the shaft.

Further objects of the invention are to provide a sectional collar which is comparatively simple and inexpensive in its construction, which can be readily applied to a 25 shaft or removed therefrom, and which is not liable to become accidentally disengaged from the shaft after being placed in position.

With these and other objects in view, the invention consists in certain novel combina- 30 tions and arrangements of the parts as will more fully appear as the description proceeds, the novel features thereof being pointed out in the appended claim.

For a full understanding of the invention, 35 reference is to be had to the following description and accompanying drawings, in which:—

Figure 1 is a front elevation of a sectional collar constructed in accordance with the 40 invention, showing the two halves thereof as about to be applied to a shaft from opposite sides thereof.

Fig. 2 is a similar view with the sectional collar in position upon the shaft.

Fig. 3 is a detail perspective view of one 45 set of interlocking ends of the collar.

Fig. 4 is an enlarged transverse sectional view through the interlocking tongues at one side of the collar, said view being taken on 50 the line 4—4 of Fig. 2.

Corresponding and like parts are referred to in the following description and indicated in all the views of the drawings by the same reference characters.

55 Referring to the drawings, which illustrate one embodiment of the invention, the

numeral 1 designates a shaft, and the numerals 2 and 3 complemental semicircular sections of the collar. The extremities of the semicircular section 2 are provided with circumferentially projecting dove-tail tongues 4 which extend the full width of the collar and have the inner sides thereof flush with the inner periphery of the collar, while the other sides thereof are beveled at 4^a. In 60 a somewhat similar manner the ends of the semicircular sections 3 are provided with circumferentially projecting dove-tail tongues 5 which extend the full width of the collar and have the outer sides thereof flush 65 with the outer periphery of the collar, while the inner sides thereof are beveled at 5^a. In assembling the two sections 2 and 3 of the collar, they are applied to the shaft 1 from opposite sides thereof and brought together in different planes, being subsequently moved longitudinally upon the shaft 70 75 1 into the same plane. This latter movement causes the beveled faces 4^a of the tongues 4 to interlock with the beveled faces 80 5^a of the tongues 5 in such a manner as to hold the two sections 2 and 3 together and prevent them from pulling apart. It will also be noted that the beveled face 5^a of the tongue 5 is formed with a longitudinal rib 6 85 of which the sides incline outwardly toward the sides of the collar, while the beveled face 4^a of the tongue 4 is formed with a corresponding depression 7. When the two sections are assembled the ends of the section 90 3 spring outwardly slightly to admit of the rib 6 entering and being seated in the depressions 7, and the two sections of the washer are thus held against accidental lateral movement relative to each other, al- 95 though they can be readily forced apart when it is desired to separate the sections and detach the collar from the shaft.

Having thus described the invention, what I claim as new and desire to secure by Letters Patent, is:—

A sectional collar including complemental segmental sections adapted to be applied to a shaft from opposite sides thereof, one of the sections being provided at its ends 105 with circumferentially projecting dove-tail tongues of which the outer faces are undercut, while the other segmental section is provided at its ends with circumferentially projecting dove-tail tongues of which the inner 110 faces are undercut and adapted to interlock with the undercut faces of the first men-

tioned tongues to prevent the two sections from pulling apart, one set of undercut faces being provided with longitudinal ribs, while the other set of undercut faces are provided with corresponding depressions adapted to interlock with the ribs to prevent lateral disengagement of the sections.

In testimony whereof I have signed my name to this specification in the presence of two subscribing witnesses.

CLYDE S. OSBORN.
